(57) **CLAIM**

The ornamental design for a wearable pet treat pouch, as shown and described.

DESCRIPTION

FIG. 1 is a perspective view of the wearable pet treat pouch, in place as worn on the belt of a user;

FIG. 2 is a front view of the wearable pet treat pouch;

FIG. 3 is a rear view of the wearable pet treat pouch;

FIG. 4 is a side elevational view of one side of the wearable pet treat pouch;

FIG. 5 is a side elevational view of the opposite side of the wearable pet treat pouch;

FIG. 6 is a top view of the wearable pet treat pouch; and,

FIG. 7 is a bottom view of the wearable pet treat pouch.

The broken line showing of a users shirt, pants and belt on FIG. 1 is for illustrative purposes only and forms no part of the claimed design.
